UNITED STATES PATENT OFFICE.

EDWARD A. RIX, OF SAN FRANCISCO, CALIFORNIA.

AIR-COMPRESSOR.

1,002,760.

Specification of Letters Patent.

Patented Sept. 5, 1911.

Application filed August 17, 1909. Serial No. 513,291.

To all whom it may concern:

Be it known that I, EDWARD A. RIX, citizen of the United States, residing in the city and county of San Francisco and State of California, have invented new and useful Improvements in Air-Compressors, of which the following is a specification.

My invention relates to air compressors.

The object of the present invention is to provide a simple, cheap, light, practical, economically operated compressor, particularly designed to meet the demands of the lesser industrial arts as well as the greater.

Modern air compressor construction has resulted in the production of heavy, ponderous and expensive machines which are slow moving, with intricate valve mechanisms, and subject to great wear. Although such machines may be economical in operation, the first cost and the weight of such compressors limit their field of operation. Realizing that air is an extremely light and elastic fluid, and that in a successful compressor small clearances must prevail, I have designed and put into extensive successful practice a compressor construction that is in harmony with the fluid to be pumped, and one whose first cost is but a small fraction of the cost of the compressors ordinarily in use.

The invention consists of the parts and the construction and combination of parts as hereinafter more fully described and claimed, having reference to the accompanying drawings, in which—

Figure 1 is a vertical section of the invention partly in elevation. Fig. 2 is a view of the loose valve disk. Fig. 3 is a detail of the stop plate and piston head.

In the embodiment of the invention, A represents a compressor cylinder of suitable size provided with a water-jacket 2 and with one or more air inlets 3, which latter communicate with the annular space 4 in the cylinder casing. This annular space 4 is in constant communication with an annular groove or channel 5 in the trunk piston 6 through either the upper or lower annular ports 7—7' in the casing; the width of the circumferential groove 5 on the piston and the position of the ports 7—7' being proportioned to the piston travel, so that practically the air is always at atmospheric pressure in space 5, and the latter is always in open communication with the outer atmosphere. This annular space 5 and the double

set of ports 7—7' constitute one of the main features of the present invention, as will be more particularly explained hereinafter.

From space 5 in the piston the air passes on each alternate reciprocation of the piston, through ports 8 formed in the end of the piston, into the compression chamber 9; the ports 8 being closed during compression by the loose disk inlet valve 10. The opening movement of the disk inlet valve 10 is limited by a stop plate or a follower plate 11 screwing or otherwise secured in the head of the piston. This disk inlet valve 10 and its stop plate 11 are also important and essential features of the invention, in conjunction with the air inlet chamber 5.

12 is a discharge valve comprising a flat casting seating on the top end of the cylinder and normally closed by the spring 13, this valve being suitably guided, as here shown, by the walls of the counterbore 14. It will readily be seen that the piston may touch this valve at the end of the stroke and make nearly a perfect displacement, and on account of the large periphery of the valve it need rise but a trifle to give ample discharge area, the air piston completely filling the cylinder on each up stroke, and the highest volumetric efficiency is attained.

Suitable packing rings 15—16 are placed above and below the air inlet space 5 to keep the piston tight, the lower ring especially being used to prevent the air coming into the space 5 from the crank-case when the device is operating as a vacuum pump, or whenever a suction unloader is employed, as is common in air compressors where a suitable compression has been obtained and it is desired to save power. In case the machine is operating as a vacuum pump, were it not for the lower snap ring 16, the suction created between the piston and cylinder would cause the air to rush in through the crank-case and around the bearings, drawing the oil out of the bearings and causing heating of the bearings.

The inlet valve 10 is stamped from thin material, like tin, or Russia iron plate, and needs no spring to keep it on the seat or to close it. It is simply in the form of a thin, flat ring or disk loosely surrounding the central stem 17 of the stop plate 11, and has an extremely limited play between the stop plate and the adjacent end of the piston.

The quick closing of the valve over the ports 8 is accomplished at the lower end of

the stroke by making the lift extremely small, and a very important part of the present invention is the discovery that I can use a lift which is but a small fraction of the lift common in all other pumps on the market. Ordinarily if the inlet valve is permitted to lift any great amount, and the compressor is running at high speed, the piston will have made quite an appreciable part of the return stroke before the valve closes, with a consequent volumetric loss. In my compressors, of which I have put a great many on the market, I never give over $\frac{1}{8}$ of an inch lift, and ordinarily $\frac{1}{16}$ of an inch, and even under some circumstances $\frac{1}{64}$ of an inch lift; the amount of lift being determined by the distance between the stop plate 11 and the end of the cylinder. By screw-threading the stem 17 of the stop plate 11 into the piston, the amount of lift may be easily adjusted to the requirements of a particular case. The inlet disk valve 10 and the stop plate 11 are of approximately the same diameter, the stop plate usually being a trifle wider than the disk valve, but both being of less diameter than the cylinder bore, so as to permit air readily to pass around their perimeters into the compression chamber 9. While this very small lift creates perhaps two or three ounces of vacuum in the cylinder when the piston is moving downward to suck in air, this slight vacuum is desirable because it holds the valve disk snug up against the under side of the stop plate 11, and so prevents chattering and fluttering and practically obviates wear. Such slight vacuum as is created is immediately dissipated as soon as the piston reaches the lower end of its stroke and before reversing, when the cylinder is put for an instant in communication with the atmosphere, making a perfect filling. Another important feature of this inlet valve construction 10 is that the slight lift of the valve and the opposed flat parallel surfaces afforded by the end of the piston and the under side of the stop plate 11 keep the valve at all times perfectly straight and obviate beating or warping of the valve, so that on the compression stroke the valve is always sure to seat smooth and tight. By this construction there is practically no wear on this inlet valve, and it will last indefinitely.

55 It is to be noted that in this compressor the spaces 4—5, and ports 7—7' are annular, thus giving a balanced and even flow of air.

This machine has shown remarkable efficiency in practice, some machines running at 500 R. P. M., giving as much as 15% increased volumetric efficiency over the best slow type machines with ordinary poppet valves. Furthermore, the cost to manufac-

ture a machine is small, by reason of this valve arrangement, due to the fact that 65 there is very little machine work necessary. I have successfully used ordinary sheet tin for my disk inlet valve 10.

Having thus described my invention, what I claim and desire to secure by Letters Patent is—

1. In an air compressor, the combination with a cylinder having an eduction valve at its upper end and two annular series of inlet ports at an intermediate point, spaced apart 75 longitudinally of the cylinder, of a crank shaft, a connecting rod and a piston movable downwardly to open the upper series of inlet ports above the piston and having a peripheral air chamber open to the inlet 80 ports in all positions of the piston when the inlet ports are not open to the cylinder, whereby the inlet ports are never closed by the piston, and an upwardly opening valve in the piston through which air passes from 85 the peripheral chamber to the cylinder.

2. In an air compressor, the combination with a piston having a peripheral air chamber, an upwardly opening valve for closing communication between the air chamber and 90 space above the piston, a driven crank shaft and a connecting rod between the crank shaft and piston, of a cylinder in which the piston works having an eduction valve at the upper end and two annular series of inlet 95 ports spaced apart longitudinally of the cylinder a distance to maintain one series open to the peripheral air chamber in the piston or to the cylinder above the piston at all times, whereby the volumetric capacity 100 of the compressor is increased and the closing of the piston valve is facilitated.

3. An air compressor embodying a piston having a peripheral air chamber intermediate its ends closed against communication 105 with the space below the piston and a disk check valve controlling communication between the chamber and space above the piston, of a cylinder in which the piston works having an eduction valve at the top and two 110 annular series of inlet ports arranged in the cylinder wall, one only of which registers with the peripheral piston chamber when the piston approaches opposite extremes of its movement, and both of which register 115 with said chamber when the piston is in a position intermediate the ends of its movement.

In testimony whereof I have hereunto set my hand in the presence of two subscribing 120 witnesses.
